SAND SCATTERER

Pearl A. Watson, Auburn, Ind., assignor to Waldo N. Dull and Paul Mutzfeld, both of Butler, Ind.

Application October 13, 1937, Serial No. 168,767

1 Claim. (Cl. 209—405)

This invention relates to improvements in grid attachments for sand scatterers of the type that are ordinarily used in conjunction with a truck or other carrier for spreading sand, cinders or the like over icy streets or roadways.

An object of the invention is to provide a detachable grid for the upper end of the hopper for a sand distributing appliance so arranged that when sand or other loose abrasive material is manually shoveled onto the grid and the sand distributing appliance is operated the undersize material passes into the hopper while the oversize material is automatically returned into the truck body from which the sand was previously shoveled.

Another object of the invention is to so construct the grid that when placed in the upper end of the hopper it will readily assume its proper slanting position therein and maintains such position without requirement of securing bolts during operation.

Other objects and advantages of the invention will appear in the following description.

An illustrative embodiment of the invention is shown in the accompanying drawing, in which:

Fig. 1 is a perspective view of a sand distributing appliance with the invention applied thereto;

Fig. 2 is a side elevation of the sand distributing appliance including the invention, the sand distributing appliance being mounted upon a truck body in position for use; and

Fig. 3 is a fragmentary side view of a hopper for the sand distributing appliance and the invention positioned therein, the view being in vertical section.

The sand distributing appliance illustrated is of a well known type that generally has a supporting frame 1 provided with elbow arms 2 that extend from its forward upper end, said arms being provided with corresponding clamp members 3 so that when the sand distributing appliance is in operating position in connection with a vehicle body 4, the frame rests against the tail gate or wall 5 of the body and the arms 2 depend into the body and the clamp members are screwed against the inner face of the tail gate, thus holding the sand distributing appliance in place.

The frame has mounted therein a hopper 6 that is pivotally mounted upon a rod 7 the ends of which are secured in the front and back of the frame at the upper end thereof. The hopper has oscillatory movement on the rod and is yieldingly held in one extreme position by a tension spring

8 that is secured at its ends respectively to the hopper and the frame, and is moved to its other extreme position in opposition to restraint of the spring by a cam 9 that is secured on a drive-shaft 10, and bears against a friction plate 11 on the hopper. Thus, when the drive shaft is rotated the hopper accordingly is vibrated. A nozzle 12 is adjustably mounted in the lower end of the frame 1 through which material from the hopper is discharged, there being a gate valve 13 provided with an operating rod 14 for controlling the discharge of material from the hopper.

The drive shaft 10 is actuated by any suitable means, such as a crank 15, that is connected with the shaft by gearing (not shown) contained in the gear case 16. Or, if preferred, any suitable motor (not shown) may be used instead of the crank operated gearing. Upon the lower end of the drive shaft 10 is concentrically secured a scatter-wheel consisting of a disc 17 having secured upon its upper face a series of radially disposed blades 18, so that when the wheel is rotated and the material passes onto the wheel from the nozzle, the material is scattered upon the road.

Preferably, the front and back walls 6'—6'' of the hopper diverge upwardly, and the upper end of the front wall 6' has secured along its top an angle iron 19, the upper flange of which extends inwardly respecting the hopper, and is for the purpose hereinafter set forth.

The grid attachment is constituted of a rectangular frame 20 the rear end of which slants upwardly and outwardly, and the front end is formed of a plate constituting a chute 21 that has secured to its rear under side, extending parallel therewith and transversely respecting the frame, an engaging bar 22 provided with a forwardly extending flange 23 spaced from the lower face of the chute 21 so that when the frame is positioned in the hopper the flange extends beneath the upper flange of the angle iron 19 while the rear end of the frame 20 rests against the slanting inner face of the back wall 6'' of the hopper. In this manner the frame is locked within the hopper. Secured in connection with the frame 20 are a series of grid bars 24 that are spaced apart in parallel relation with each other and extend from the rear end of the frame over onto the top of the chute 21 and are suitably secured thereon.

In use, the sand distributing appliance is secured preferably to the tail gate 5 of the truck body and clamped in position thereon by tightening the clamp members 3. The scatter-wheel 15

- is then set in motion by turning the crank 15, and while the truck is in motion the abrasive material is manually shoveled onto the grid. The undersize material passes through the grid and falls into the hopper and is kept agitated while passing therethrough by the vibratory action of the hopper, and from thence it is discharged through the nozzle onto the scatter-wheel by which it is distributed over the surface 5 of the roadway. The oversize material, upon failing to pass through the grid bars, aided by the vibratory action of the hopper, slides downwardly over the grid bars and the chute back into the truck body.
- 10 15 When it is desired to remove the grid it is only necessary to raise the rear end of the grid frame and move it rearwardly so as to remove the flange 23 from engagement with the angle iron 19, and then lift the grid bodily from the hopper. In replacing the grid it is held above the 20 top of the hopper with the chute resting upon

the angle iron 19 and then moved upwardly so that the flange 23 is moved under the inturned flange on the angle iron while the rear end of the grid is dropped down into position against the rear wall 6" of the hopper. 5

What I claim is:

In an apparatus of the class described a vibratory hopper having upwardly divergent front and rear walls, the rear wall extending above the front wall and being downwardly and forwardly inclined, the front wall having an inwardly directed flange at its top; the combination therein of a screen grid provided with a frame and having a chute at its forward end, resting on said flange, an angle member secured 10 to the bottom of said chute and having a forwardly extending portion engaging the underside of said flange, the rear edge portion of said frame resting on the inner face of said rear wall below the top thereof. 15
